UNITED STATES PATENT OFFICE.

ROBERT JOHN RILEY, OF ZION CITY, ILLINOIS.

DETACHABLE RECEPTACLE-HOLDER.

SPECIFICATION forming part of Letters Patent No. 781,228, dated January 31, 1905.

Application filed February 19, 1903. Serial No. 144,149.

To all whom it may concern:

Be it known that I, ROBERT JOHN RILEY, a citizen of the United States, residing at Zion City, in the county of Lake and State of Illinois, have invented a new and useful Detachable Receptacle-Holder, of which the following is a specification.

The present invention relates particularly to means for holding ordinary tin cans and converting the same into useful household utensils, though said holders may be employed in connection with receptacles of various kinds, as will be apparent after the nature of the invention is more fully understood.

It is the object to provide a holder of this character which is simple in its structure, can be readily and securely applied to a can or receptacle, and when the same is worn out or damaged said holder can be removed therefrom and applied to another.

The preferred embodiment of the invention is illustrated in the accompanying drawings and is described in the following specification.

The construction set forth is open to various changes and modifications without departing from the spirit of the invention.

In the drawings, Figure 1 is a perspective view of the holder when in place upon a receptacle. Fig. 2 is a horizontal sectional view through the same. Fig. 3 is a perspective view of the holder when detached.

Similar reference-numerals indicate corresponding parts in all the figures of the drawings.

In the embodiment herewith illustrated a pair of spaced receptacle-embracing clasps in the form of compressible and extensible loops 10 are employed, and to the same is attached a handle, (designated as a whole by the reference-numeral 11.) The handle is preferably a single wire doubled to form separate sections comprising arms 12, having offset fingers 13 at their ends, said fingers being provided with outstanding portions 14. The shank of the handle formed by the arms 12 is preferably contracted toward its outer end, and said arms are connected by an enlarged loop portion 15.

The receptacle-embracing loops 10 are preferably constructed of sheet metal, and their corresponding terminals are bent about the

fingers 13, the ends being arranged against the inner faces of said loops. It will thus be seen that when the handle is compressed, or, in other words, when the sections thereof are brought together, the loops will in like manner be compressed, and for the purpose of holding them in such condition a hook 16 is pivoted upon the outstanding portion 14 of one finger and detachably engages the outstanding portion of the other finger. An auxiliary to this holding-hook is a keeper 17, which is slidably mounted on the arms 12 and connects the same, said keeper when moved toward the handle-loop 15 permitting the expansion of the loops and when moved toward the inner ends of the arms drawing said loops together.

An ordinary metallic preserving-can is illustrated in the drawings and designated by the reference-numeral 18. These cans are preferably employed in connection with the holder, as they may be readily procured, are of determined capacities, and will have smooth edges after their tops have been removed. In applying the holder to a receptacle the loops are made of sufficient size to snugly embrace the same, and this may be readily accomplished because of the adjustable connections between said loops and the handle. The receptacle is then placed within the loops and the keeper 17 is moved toward the inner ends of the handle-arms, after which the other end of the holding-hook is engaged with the outstanding portion of the adjacent finger. As a result, the receptacle will be tightly bound within the compressed loops and a convenient dipper, measure, or cooking utensil is provided. When the receptacle becomes worn out or injured, it may be replaced by a new one. It will be apparent that the device may be manufactured at small cost, as it is constructed entirely of wire and sheet metal, the parts, moreover, being very simple.

From the foregoing it is thought that the construction, operation, and many advantages of the herein-described invention will be apparent to those skilled in the art without further description, and it will be understood that various changes in the size, shape, proportion, and minor details of construction

may be resorted to without departing from the spirit or sacrificing any of the advantages of the invention.

Having thus fully described my invention, 5 what I claim as new, and desire to secure by Letters Patent, is—

1. In a holder of the class described, the combination with a handle comprising spaced members, each having an offset finger at one 10 end, said fingers being provided with outstanding portions located in spaced relation to the handle, a compressible receptacle-embracing loop having ends connected with the fingers between the outstanding portions and the handle 15 members, a device connecting the handle members, and a device connecting the outstanding portions of the fingers for holding the loop in compressed condition upon a receptacle, said devices being located on opposite 20 sides of the ends of the loop.

2. In a holder of the class described, a handle element comprising a doubled wire form-

ing spaced members, the terminals of said wire being offset from the handle members and constituting fingers, said fingers having spaced 25 alined portions connected by intermediate outstanding portions, compressible receptacle-embracing loops having their ends attached to the alined portions of the fingers, a hook pivoted upon one of the outstanding portions and 30 detachably engaging the other, said hook being located between the loops, and a holding device mounted upon and connected with the members of the handle, said hook and device constituting means for securing the loops in 35 compressed condition upon a receptacle.

In testimony that I claim the foregoing as my own I have hereto affixed my signature in the presence of two witnesses.

ROBERT JOHN RILEY.
